REEL

Filed Dec. 17, 1927

UNITED STATES PATENT OFFICE

SAMUEL E. COWLES, OF WORONOCO, MASSACHUSETTS, ASSIGNOR TO STRATHMORE PAPER COMPANY, OF MITTINEAGUE, MASSACHUSETTS, A CORPORATION OF MASSACHUSETTS

REEL

Application filed December 17, 1927. Serial No. 240,830.

This invention relates to improvements in reels for winding up webs of material such as paper or the like.

In connection with the manufacture of paper, fabrics or the like, it is an ordinary step to wind or reel up at some stage of the process a web of paper or fabric onto a reel or arbor. For instance, in paper manufacturing, as a web of paper leaves a drying apparatus where it is dried, the web is led onto a rotating reel or arbor which takes up or winds up the web into the form of a roll; and then, as a subsequent step, the web is led from the roll on this reel and passed through other apparatus such as a slitting and trimming machine and is wound up again on another reel. There are many other and varied instances where a web of material such as a paper or fabric web, which is wound up on one reel, is led from the reel and through some apparatus or other and again wound up on another reel. The reels referred to usually comprise a plurality of longitudinal wooden bars or slats arranged circumferentially of circular head members at the ends thereof.

As the web of material is wound up by the reel to form a roll, there is a tendency for the web to shift sideways of the roll and reel so that the edges of the web forming the roll on the reel bulges in places either on one end of the roll or the other; that is, the ends of the roll formed by the rolled up web are often uneven so that the ends of the roll are not flat and true. This is objectionable because as the web is subsequently unwound from the reel and fed through other apparatus for various operations the edges of the web do not run true. In order to properly guide the web into the apparatus, the reel and roll must be moved axially back and forth while the web is being unwound so that the edges of the web are aligned properly with the apparatus which receives it.

It has become an ordinary but dangerous practice while the reel is taking on or winding up a web, to nail boards onto the reel at the side edges of the web or ends of the roll in an attempt to cause the web to wind up evenly or so that the ends of the roll are flat and even. This practice is not only ob-

jectionable because a dangerous condition exists as the boards which extend from the reels rotate at high speed, but because the nailing on of the boards injures the bars or slats of the reels.

I overcome the above objections and disadvantages by providing a reel which will wind up or roll up a web into the form of a roll which will have flat even ends. This is accomplished according to the novel features of the invention by providing a reel, which has guide members for embracing or guiding the side edges of the web onto the reel which are relatively movable or adjustable, so as to guide webs of various widths and direct or guide the web onto the reel and embrace or confine the ends of the roll so as to form a roll having flat, smooth, even ends.

The invention is adapted for broad application but for descriptive purposes will be disclosed in connection with a reel adapted for use in connection with paper manufacturing apparatus and in the form at present preferred is shown in the accompanying drawings, in which:

Fig. 1 is a longitudinal sectional view of a reel embodying the novel combination and arrangement of parts forming the invention;

Fig. 2 is an enlarged sectional elevational view taken on the line 2—2 of Fig. 1;

Fig. 3 is an enlarged sectional view showing in detail the method of securing the guide pilot to the reel guide;

Fig. 4 is a small scale perspective view of certain of the parts; and

Fig. 5 is a small scale elevational view showing the reel carrying a roll of paper which is guided by the guides on the reel.

By reference to the drawings, the novel combination and arrangement of parts will now be described. 1 represents a tubular or hollow supporting arbor for the reel which is provided with longitudinal slots 2 as shown and has fixed thereto in some convenient manner a plurality of reel supporting collars 3.

A rod 4 extending through the arbor 1 is journalled for rotation in a bearing member 5 fixed to the arbor and is held against axial or endwise movement by a collar 6 and nut 100

7 carried thereby which are disposed on opposite sides of the bearing member 5. A threaded sleeve 8 is fixed to the rod so as to be rotated thereby, but in lieu thereof the end of the rod may be threaded if desired.

5 A sleeve 9 which fits over the rod 4 is rotatable with respect thereto and is journalled for rotation independent of the rod 4 in a bearing 10 fixed to the support 1. This 10 sleeve is held against axial displacement in the tube by thrust collars 11 and 12 fixed thereto which are disposed at opposite sides of the bearing 10 and is provided with a threaded portion 13 for the purpose soon to 15 be described. Operating wheels or handles 14 and 15 are fixed to the ends of the shaft 4 and sleeve 9 so that they may be relatively and independently rotated with respect to one another and with respect to the supporting arbor 1.

20 Longitudinal slats or bars 20 are disposed about the circumference of the collars 3 and are secured thereto by bolts or in any convenient manner and are arranged to form the reel body R for receiving and supporting a web of paper or the like. Slots 21 are provided at either end of the body R which are preferably in line with the slots 2 of the arbor 1 previously described. Internally 25 threaded members 25, which may be called nuts, are in threaded engagement with the threaded sleeves 8 and 13 and are arranged to slide within the arbor 1. One of the sleeves and its nut may be made with left 30 hand threads while the other may be made with right hand nuts, but this is not important, it being intended that the construction will be such that the nuts will be moved independently of one another and in one direction or the other accordingly as the rod 4 or sleeve 9 is rotated to move or adjust its respective nut along the arbor.

40 Members 30 in the form of brackets are secured to the nuts by any suitable means such as bolts or the like and have at their 45 lower sides a guide portion 31 which is arranged to fit within the slots 2 of the arbor so that as they are moved longitudinally of the arbor by their respective nuts they will 50 be held in an upright position and prevented from turning with respect to the arbor.

55 The upper side of the brackets extends upwardly into the slots 21 of the reel and are provided with tapering openings 40 for receiving pilots 41 of guide members G. An annular seat 41' adjacent the lower end of the pilot receives a lock member 42 in the form of a ball which is carried by the bracket 60 30 and which is urged forwardly by a plunger 42' and spring 43, the spring and plunger being confined in a tube 30' secured to the member 30. With this arrangement the pilot is resiliently held by the lock member 65 so that it may be quickly inserted in or

withdrawn from the bracket whenever desired.

Obviously other means than that shown may be provided for detachably holding the guide in the bracket member.

The guides may take any form desired but as here shown preferably comprise a plate member 50 of some fibrous material which is made in the form of a crescent that is reinforced by straps 51 which are secured to and carried by a staff 52 fixed to the pilot 41.

70 The reel may be made for use in connection with any ordinary form of reeling apparatus such as shown in Fig. 5. In the form shown, the apparatus may comprise a pair of journal bearing supports 60 which are adapted to receive the arbor 1 so that it may be rotated therein. Collars 61 may be secured to the arbor at the sides of the journal bearings to hold it against an endwise shifting movement and a pulley such as 62 may be secured to the end of the arbor for receiving a driving belt or the arbor may be rotated by hand or operatively connected by gearing, chains or any other means to any 80 source of power for rotating it so that the reel will wind up a web into the form of a roll.

85 Assuming that the reel is to be employed for winding or reeling up a web of paper to 90 form a roll as it comes from a drier or the like: the web is led onto the reel which will be rotated by some means as described; and then, by turning the hand wheels 14 and 15, the guides are moved independently of one 95 another so that they align with and embrace the side edges of the web so as to guide the web onto the reel. As the web is wound up by the reel into the form of a roll, the web, which is confined by the guides and held 100 against endwise movement, will produce a roll which will have smooth, flat and even 105 ends as is desirable.

110 By providing the independently movable and relatively adjustable guides, they may be adjusted or disposed so as to embrace various widths of material and may be adjusted to accommodate themselves to and guide the web onto the reel should it be desired or necessary to build up the roll at a point nearer one end of the reel than the other.

115 By thus providing a reel which will form a roll which has the even, flat ends, the web may easily be unrolled therefrom and led onto another reel without any sideways shifting movement of the web as it runs from one reel to another and therefor the necessity of manually shifting the reel and roll to compensate for any irregularity caused by uneven 120 rolling up of the web is eliminated.

125 I am aware that many changes may be made in the form of the apparatus to adapt it for various purposes and I prefer to be limited, if at all, by the appended claims rather than 130

the foregoing description of the present preferred form of the invention.

What I claim is:

1. A reel for winding up a web of material comprising in combination, an arbor and reel body supported thereby, relatively and independently rotatable members in said arbor, guide members guided in said arbor for independent movements thereon and connections between said guide members and rotatable members whereby the guide members are moved on said arbor by said rotating members.
2. A reel for winding up a web of material comprising in combination, an arbor and reel body supported thereby having aligned slots, relatively and independently rotatable members in said arbor, guide members in engagement with said rotatable members extending through said slots and means connecting said members and guides whereby they are moved along said slots accordingly as the members are rotated.
3. A reel for winding up a web of material comprising in combination, an arbor and reel body supported thereby, relatively and independently rotatable screws in said arbor, guide members in threaded engagement with said screws and guided in said arbor which are moved by a rotation of said screws.
4. A reel for winding up a web of material comprising in combination, a supporting arbor and a reel body carried thereby having aligned guide receiving slots, rotatable members in said arbor arranged for independent and relative rotative movements, screws carried thereby, guides guided in said slots and in threaded engagement with said screws whereby as the members are rotated the guides will be moved with respect to the reel and arbor.
5. A reel for winding up a web of material comprising in combination, a slotted arbor, a reel body supported thereby for rotation therewith, a rod extending through said arbor and bearing threads at one end, a sleeve rotatably surrounding the rod and bearing threads upon its outer surface, both the rod and the sleeve extending beyond the end of the arbor so as to be independently rotatable with respect thereto, a pair of nuts threaded respectively upon the rod and the sleeve and having sliding engagement with said slots, and crescent-shaped guide members detachably connected to said nuts.

In testimony whereof I have affixed my signature.

SAMUEL E. COWLES.
